JOSEPH WATKINS, OF FORT WAYNE, INDIANA, AND FORD D. ECHLER, OF WEST UNITY, OHIO.

SAFETY DETENT FOR SPLIT SWITCHES.

Application filed March 12, 1923. Serial No. 624,367.

To all whom it may concern:

Be it known that we, JOSEPH WATKINS, citizen of the United States of America, and resident of Fort Wayne, in the county 5 of Allen and State of Indiana, and FORD D. ECHLER, citizen of the United States of America, and resident of West Unity, in the county of Williams and State of Ohio, have invented certain new and useful Im- 10 provements in Safety Detents for Split Switches, of which the following is a specification.

This invention relates to improvements in safety detents for split switches of that 15 class employed for holding the switch in closed position. The object of the improvement is to provide a detent for holding a switch point in closed position independently operable respecting the switch stand 20 or other mechanism for throwing the switch.

It frequently occurs in railway operations that the stand for operating the switch is broken away from its connection with the switch, and the switch is left loose without 25 any means of preventing it from opening with more or less serious consequences. The present invention is intended as an expedient for retaining the switch in closed position even though the switch operating mechanism 30 becomes completely disabled. Another object is to so construct the device as to be operated by the movement of the switch itself, and also in such manner as not to interfere with the switch while in open position.

These objects are accomplished by the construction illustrated in the accompanying drawings, in which:—

Fig. 1 is a plan view of a split switch and its operating mechanism, and including also 40 the present invention applied to the switch; and

Fig. 2 is a side view of a construction embodying the invention showing the same in connection with a railroad stock rail and 45 corresponding switch point.

The characters appearing in the description refer to parts shown in the drawings and designated thereon by corresponding characters:

50 The invention comprises a housing 1 having a cover 2 which is held thereon by lag-screws 3 that extend through the cover and the housing into the head block 4 against

the side of which the housing is secured. At one end of the housing, projecting from the top thereof, is a jaw 5 that fits over the adjacent side of the foot of the stock-rail 6. Within the housing is a longitudinally movable latch-bar 7 in the underside of which is made a recess 8, there being an angular shoulder 9 at one end of the recess. One end of the bar extends through the end of the housing beneath the jaw 5 and has a pin 10 upon which is secured an eyebolt 11. The switch point 12 has connection with the eyebolt 11 through the medium of a bracket 13 that is riveted to the switch point and is held between lock nuts 14 on the eyebolt. Thus, when the switch point is moved open or closed, longitudinal movement will be imparted to the latch-bar accordingly.

In the lower part of the housing is an inclined face 15 at the upper end of which is formed a recess 16, and arranged partially in said recess 16 and in the recess 8 in the bar is a movable head 17 that has a stem 18 extending loosely through a lug 19 fixed in the housing, there being a compression spring 20 on the stem between the head and the lug. The head 17 has rollers 21 and 22 80 that bear respectively against the bar 7 and the face 15.

In the operation of the invention, when the switch point is closed the latch-bar is held in its innermost position by the head 85 17 which bears with the force of the compression spring against the shoulder 9 on the bar, and thus the switch point is retained in closed position. When the switch point is opened by the switch operating mechanism 23, the latch-bar 7 is drawn out accordingly and the head 17 is forcibly moved against the compression of the spring until it passes downwardly upon the inclined face 15 to such an extent that it becomes disengaged from the shoulder 9 and thus releasing the bar. While the switch point is in its open position, the latch-bar is relieved of the end thrust of the head as at such times the head bears upwardly against the bottom face of the latch-bar, so that said bar may be moved freely. As the switch point is closed, the bar is moved inwardly 95 so that the head re-enters the recess 8 therein and bears against the shoulder tensionally, holding the latch-bar in its innermost 100 105

position. In this manner when the switch point is closed it tends to remain closed, and when opened is free to remain open even though the switch operating mechanism be disconnected entirely.

The housing is preferably designed so that when in place, its top, with the exception of its jaw 5 will lie in the plane of the tops of the head block and ties 24 where it 10 will not be exposed to accidental dislodgment.

What we claim is:—

1. In a safety detent device for a split switch having a movable switch member, a 15 housing; a longitudinally movable latch bar in the housing; having a recess and shoulder; an adjustable connecting means between the latch-bar and the movable switch member; an inclined face formed in the 20 housing opposite the recess in the latch-bar; and a spring pressed member having bearing relation against the shoulder of the latch member and said inclined face.

2. In a safety detent device for a switch 25 having a movable switch member, a fixed housing having therein an inclined face; a latch-bar having a shoulder and operative relation with the switch member, said latch-bar extending into the housing; and a 30 spring pressed movable member bearing on said inclined face and having engaging relation with the shoulder on the latch-bar.

3. In combination with a railway track

including a movable switch-member and actuating means therefor, a latch-bar having operable relation with the switch member independent of the switch actuating means; and a spring pressed member operable to yieldingly detain the latch-bar when the switch member is closed.

4. In combination with a movable switch member, a latch-bar movable with the switch-member; and a spring actuated member operable to yieldingly detain the latch-bar when the switch member is closed, and 40 being movable from detaining engagement with the latch-bar when the switch member is opened.

5. In combination with a switch member and actuating means therefor, a sliding latch-bar having operable relation with the switch member independent of said actuating means; and a spring pressed member having detaining engagement with the latch-bar when the switch member is closed and being movable by the latch-bar from 45 detaining engagement therewith when the switch member is opened.

In testimony whereof we affix our signatures in presence of two witnesses.

FORD D. ECHLER.
JOSEPH WATKINS.
